IRVING LIFSHITZ, OF NEW YORK, N. Y.

CLOTH-CUTTING MACHINE.

1,272,818.

Specification of Letters Patent. Patented July 16, 1918.

Application filed April 5, 1918. Serial No. 226,924.

To all whom it may concern:

Be it known that I, IRVING LIFSHITZ, a citizen of Russia, and a resident of New York, in the county of New York and State 5 of New York, have invented certain new and useful Improvements in Cloth-Cutting Machines, of which the following is a specification.

This invention relates to cloth cutting machines of the reciprocating blade type and resides primarily in the means for sharpening blades. In machines of this character the blade is ordinarily secured at its upper end to the operating mechanism and is guided 10 in the standard which supports said mechanism from the base. The lower end of the blade is free and the range of movement is such that said lower end alternately enters and rises above a slotted throat plate substantially flush with the base. The blade is not only sharpened along its front edge but is also sharpened across at least a part of the lower end. Thus the knife during the 15 downward movement cuts not only with the front edge but with the lower end.

The front edge of the blade may be readily sharpened to the desired rough cutting or ripping edge without removing the blade from the machine but the cutting edge across 20 the lower end must be sharpened to a razor edge and it is this part which becomes dulled the most rapidly. In no machine with which I am familiar can this be done without the delay and trouble incidental to the removal 25 of the blade from the machine.

The main object of my invention is to provide a sharpening mechanism particularly designed to operate on this lower end portion of the blade and which may be attached 30 to and permanently carried by the machine in such a way as to not in any way interfere with the free normal use of the machine in the cutting of the cloth. In its preferred embodiment I employ a sharpening mechanism 35 including a pair of rollers of appropriate material to act as grinders and position them in the comparatively small space beneath or within the base. As important features of my invention I so mount the 40 grinders and their supporting and adjusting mechanism so that they may be readily removed from the machine at will and may be readily applied to any type of reciprocating blade cloth cutting machine. Means are provided whereby the grinders may be separated 45

and held in inoperative position or released for grinding operation in a very simple manner. The parts may be removed or replaced without the use of any special tools and without requiring the skill of experienced machinists. 60

In the accompanying drawing I have illustrated one embodiment of my invention although it will of course be evident that this is to be considered in an illustrative rather 65 than in a limiting sense and that various changes may be made within the scope of the invention as defined in the appended claims.

In these drawings:

Figure 1 is a top plan view of a portion 70 of the base of a machine, the standard and blade being shown in section.

Fig. 2 is a transverse section on the line 2—2 of Fig. 1, on an enlarged scale.

Figs. 3 and 4 are vertical sections approximately on the lines 3 and 4 respectively of Fig. 1. 75

Fig. 5 is a top plan view of the grinders and their support removed from the base of the machine. 80

Figs. 6 and 7 are views of the opposite ends of the parts shown in Fig. 5.

Fig. 8 is a side elevation of the parts shown in Fig. 5, the cover or throat plate being shown in dotted lines in partly raised 85 position.

Fig. 9 is a top plan view of the combined cover and throat plate.

Fig. 10 is a side elevation of the part shown in Fig. 9. 90

Fig. 11 shows one of the grinders and Fig. 12 shows one of the means for applying adjustable resilient pressure to the grinders.

I have illustrated my invention in connection with parts of a common type of cloth cutting machine. This includes a base 20, the sides and rear portions of which curve downwardly toward the supporting surface. The body has a plurality of anti-friction rollers 21 for supporting the base and the 100 remainder of the machine carried thereby and for facilitating the forward movement of the machine during the cutting operation. Pivoted or hinged to the front edge of the body is the ordinary apron 22, the front 105 edge of which rests directly upon the supporting surface and guides the base beneath the cloth to be cut. Threaded into an aperture in the base is the standard 23. The portion of this standard above the level of the 110

upper surface of the base and which passes through the cloth is made comparatively narrow as shown particularly in Fig. 1. This is also longitudinally slotted to form a 5 guiding groove 24 for the knife 25. The knife is mounted to reciprocate within this groove by operating mechanism supported at the upper end of the standard 23 but which it is not necessary to illustrate. The lower 10 end of the knife or blade is sharpened not only along its front cutting edge 26 but also along the front portion of its bottom cutting edge 27 shown particularly in Fig. 4. The blade when in its downward limiting position occupies substantially the position shown in Fig. 4, although when raised it comes some little distance above the upper surface of the base. Set in the base in front of the standard and slotted to receive the 15 knife is what is commonly known as a throat plate 28. The side and rear edges of this are preferably slightly higher than the level of the upper surface of the base as shown particularly in Fig. 2 so as to properly guide 20 the cloth to the knife, preventing its catching on the front edge of the standard and aiding in reducing friction. The parts so far described are those commonly found in cloth cutting machines of the reciprocating 25 blade type and the details thereof form no portion of my invention except in combination as hereinafter pointed out.

In carrying out my invention I provide a 30 pair of rollers 30 of such material that the rubbing engagement of the knife blade therewith will tend to sharpen the latter. They may be of the same material as ordinary oil 35 stone used for sharpening or may be of any other desired abrasive or sharpening material. These are mounted with their axes 40 parallel to and spaced at equal distances upon opposite sides of the knife blade, and within the space below the throat plate and above the level of the supporting surface 45 and upon which rests the rollers 21. The polishing or grinding rollers 30 are resiliently pressed toward each other so that when the knife is raised the two rollers are 50 in direct contact but as the knife reaches the lower end of its movement the cutting edge 27 enters between the two grinding rollers and presses them apart thereby rubbing over the surface of each and becoming 55 sharpened.

In practice, I preferably provide a housing or casing as shown particularly in Figs. 5 to 8 inclusive. This is in the form of a 60 rectangular metal box 31 having oppositely disposed outwardly extending lugs 32 adapted to receive bolts, screws, or the like, 33 threaded into the under side of the base and holding the box or casing 31 rigidly and firmly in place. The grinding rollers may be mounted in the box in various different 65 ways but preferably each roller has reduced

journal end portions 34 as shown particularly in Fig. 11 and these enter in the bayonet slots 35 as shown particularly in Fig. 2. The rollers after being dropped into the slots are moved toward each other and thereby held against any upward or downward movement. For pressing the rollers together I preferably provide suitable springs between each roller and the adjacent side of the housing. Such springs may be designed 70 in various different ways but in order to readily adjust the tension thereof, I employ two coil springs 36 for each roller, each spring setting against or being secured to a curved bearing blade 37 for engagement with the roller and a socket stop 38 threaded in an aperture in the side of the housing. By rotating these threaded stops a greater or lesser tension may be put on the springs and the rollers held together with greater or lesser pressure. I have not shown these 75 springs and their supports in Fig. 2, they being purposely omitted therefrom to more clearly show the bayonet slots 35.

The top of the box or housing is open and the housing is so positioned directly beneath the throat plate that the latter may and preferably does, serve as a cover for the housing of the grinder rollers. In the construction illustrated, the throat plate is secured to and directly supported by the housing and merely fits within the aperture in the base. The cover or throat plate 28 is shown as having two curved or hooked projections 39 adjacent to one end and a slight 90 groove adjacent to the other. The curve or hooked projection 39 may fit into apertures or depressions 40 in the end of the housing nearest to the standard and the opposite end of the housing may have a spring catch 41 for engaging in the groove at the adjacent end of the throat plate to resiliently retain the latter in position as shown particularly in Fig. 8. It will of course be understood 95 that the end of the housing nearest to the standard is vertically slotted to receive the knife as is also the bottom wall of the housing.

As it is not either necessary or desirable 100 that the grinders engage with the knife blade every time the latter comes down in cutting cloth I provide means for holding the grinders spaced apart in inoperative position whenever it is not necessary to utilize their sharpening functions. A very simple 105 means of accomplishing this result comprises a set screw 42 threaded through the bottom of the housing and having a pointed end for engagement between the two grinder rollers. By lowering this set screw out of engagement with the rollers they will be 110 pressed directly together by the springs and the knife will be sharpened during the lower portion of each stroke. By giving this set screw a few turns the pointed end will 115 120 125 130

wedge between the grinder rollers and space them apart so that they will not engage with the knife during reciprocation of the latter and the grinders will thus be held in inoperative position.

My improved device is very simple and inexpensive in construction and it is so designed that it may be applied to various different makes of machines with little if

10 any alteration in the latter. The throat plates vary somewhat in size and shape in different makes of machines but it is merely necessary to cut through the base an aperture of the proper size to receive the hous-

15 ing of my improved device and to provide a pair of threaded apertures for the attaching screws 33. The device is concealed from view and is beneath and protected from the cloth so that it does not in any way inter-

20 fere with the free movement of the machine through the cloth during the cutting operation. Any fine grit which may be produced during the grinding operation falls through and cannot come in contact with

25 any part of the machine with which the cloth may later engage, thus the cloth is protected against soiling. Any sparks which might result from the use of the device while the blade is in the cloth would either be

30 retained within the housing or would fall through to the table beneath the base and thus there is no liability of the spark setting fire to the cloth. The grinders may be very easily removed and turned end for

35 end when they become worn or the tension of the springs may be easily changed, the only tool required being a screw driver and no special mechanical skill being needed.

The condition of the grinders may be easily inspected at any time by merely forcing the spring catch 41 out of engagement with the throat plate 28 and lifting the latter. Any excess oil used on the rollers or the bearing thereof, cannot drip on to the cloth

45 as it is already beneath the level of the base over which the cloth passes. Various other advantages of my improved device and of obvious alterations thereof within the scope of the appended claims will be apparent to

50 those skilled in the art.

Having thus described my invention what I claim as new and desire to secure by Letters Patent is:

1. A cloth cutting machine having a reciprocating knife presenting a longitudinally extending cutting side and a transversely extending cutting end and a sharpening member in the path of movement of said knife and with which said transversely

60 extending cutting end may engage during the final operation of its downward stroke.

2. A cloth cutting machine having a reciprocating knife having longitudinally and transversely extending cutting edges and a

65 pair of grinder or sharpener members so

positioned that the lower end of the knife may pass therebetween and engage with both during the lower portion of its stroke to sharpen only said transversely extending cutting edge.

70

3. A cloth cutting machine having a reciprocating knife sharpened transversely of the lower end thereof and a pair of grinder or sharpener members resiliently pressed together and so positioned that the lower end of the knife may pass therebetween to separate them and engage with both during the lower portion of its stroke to sharpen only said transverse cutting end.

75

4. A cloth cutting machine having a base, a standard rising therefrom, a reciprocating knife, and a sharpener for the latter carried by the base beneath the upper surface of the latter.

80

5. A cloth cutting machine including a base, a vertically movable reciprocating knife and a pair of grinder members carried by the base beneath the upper surface of the latter for sharpening the lower end of the knife.

85

6. A cloth cutting machine having a base, a knife having a portion thereof movable therethrough and a pair of grinder members secured to the under surface of the base for engaging with opposite sides of the downwardly protruding part of the knife.

90

7. A cloth cutting machine including a base having a slot through which the cloth cutting member may extend and a pair of sharpener members carried by the base beneath the upper surface of the latter for engaging with said cloth cutting member.

95

8. A cloth cutting machine having a base, and a pair of sharpening rollers secured thereto beneath the upper surface thereof.

100

9. A cloth cutting machine including a base having a slot, a pair of sharpening rollers beneath the base on opposite sides of the slot and a knife movable downwardly through said slot between said rollers.

105

10. In combination, a cloth cutting machine base, a housing secured to the under surface thereof, and a pair of sharpening rollers within said housing.

110

11. In combination, a cloth cutting machine base, a housing secured to the under surface thereof, and a pair of sharpening rollers within said housing, and resiliently pressed together.

115

12. In combination, a housing, a pair of sharpening rollers disposed therein and resiliently pressed together and means for securing said housing to the base of a cloth cutting machine.

120

13. In combination, a housing having a pair of bayonet slots in each end thereof, a pair of rollers having their journals disposed within said slots and held against upward or downward movement, a pair of springs between each roller and the adjacent

125

130

side of the housing and means for attaching said housing to the base of the cloth cutting machine.

14. In combination, a housing having a pair of bayonet slots in each end thereof, a pair of rollers having their journals disposed within said slots and held against upward or downward movement, a pair of springs between each roller and the adjacent side of the housing, separate means for adjusting the tension of said springs, and means for attaching said housing to the base of the cloth cutting machine.

15. In combination, a housing, means for securing the same to the under side of a base of a cloth cutting machine, a pair of sharpening members within said housing, means for pressing said members toward each other and an adjustable member secured to one

wall of the housing and adapted to enter between said members for spreading them apart.

16. In a cloth cutting machine a combination of a base, a sharpening member, a housing for the latter, and a combined housing cover and throat plate.

17. In a cloth cutting machine a combination of a base having an aperture therethrough, a housing disposed within said base, a pair of knife sharpening members within said housing, and a throat plate secured to said housing and serving as a cover for the latter.

Signed at New York, in the county of New York, and State of New York, this 4th day of April A. D. 1918.

IRVING LIFSHITZ.
